UNITED STATES PATENT OFFICE.

JOHN GRAY, OF BELLE VERNON, PENNSYLVANIA.

IRONING-TABLE.

SPECIFICATION forming part of Letters Patent No. 727,351, dated May 5, 1903.

Application filed September 27, 1902. Serial No. 126,060. (No model.)

To all whom it may concern:

Be it known that I, JOHN GRAY, a citizen of the United States of America, residing at Belle Vernon, in the county of Fayette and State of Pennsylvania, have invented certain new and useful Improvements in Ironing-Tables, of which the following is a specification, reference being had therein to the accompanying drawings.

10 This invention relates to certain new and useful improvements in ironing-tables; and the main object of the invention is to construct an ironing-table which may be folded into a neat and compact form when not in use.

15 A further object of my invention is to construct an ironing-table of this class having two or more ironing boards or surfaces for the accommodation of different styles of garments or other articles being ironed upon the table.

20 Briefly described, the invention comprises a main ironing-board to which is hinged, adjacent to one end thereof, one member of the supporting-frame. The other member of the 25 supporting-frame is pivoted to the first-mentioned member and has at its upper end means for engagement with the main ironing-board, adjacent to the other end of the latter, for supporting the same. Locking means are 30 carried by the two members of the supporting-frame for holding the same in the extended position, and the main ironing-board carries one or more supplemental ironing-boards to accommodate different styles of articles 35 being ironed.

40 All the above-described construction will be hereinafter more fully described and then specifically pointed out in the claims, and in describing the invention in detail reference is had to the accompanying drawings, forming 45 a part of this specification, and wherein like numerals of reference indicate like parts throughout the several views, in which—

Figure 1 is a side elevation of my improved ironing-table in the built-up or extended form. Fig. 2 is a top plan view of the same. Fig. 3 is a top plan view of the supporting members in their extended position with the ironing-board detached. Fig. 4 is a side elevation of the device in its folded form.

To put my invention into practice, I provide a supporting member comprising a pair

of standards 1 1', which are spaced a suitable distance apart and slightly wider at their lower than at their upper ends. On their upper 55 ends each standard carries a hinge 2, and adjacent to their lower ends these standards are connected together by the cross-bar 3, suitably fastened thereto and preferably on the underneath face thereof in order that 60 the device may fold in a convenient form. The hinges 2 at the upper ends of the standards are connected to a cross-bar 4, attached to the underneath face of the main ironing-board 5. This cross-bar 4 is preferably fastened to the board by means of the bolt 6, which is of sufficient length to also secure in 65 position the supplemental ironing-boards 7 and 8, each of which is mounted so as to be rotated on the bolt 6. The supplemental 70 board 7 is mounted on the interposed block 9, carried by the main board 5 and secured by the bolt 6, while the supplemental board 8 is mounted on top of the board 7. The interposed block 9 raises the board 7 some distance 75 above the main board 5, whereby when it is swung around over said board, as shown in Figs. 1 and 2, the garment—such, for instance, as a shirt—may be drawn over the board, so that the bosom thereof will lie on 80 the upper face of the said board and the back thereof lies below the board. This is true also of the supplemental board 8, and when using this board the supplemental board 7 will be swung around so as to project 85 over the end of the board 5, while the board 8 will be moved around so as to lie over the said board 5. This board 8 is preferably made of a convenient form for ironing the sleeves of waists or the like. To the under face of the ironing-board 5, near the other end thereof, is secured a pair of notched rack-bars 10, which are adapted to receive means carried by the upper end of one of the supporting members for supporting the outer 95 end of the ironing-board. The standards 1 1' carry on their under faces at a point about midway of their length staples or eyes 11, in which is journaled the rounded ends 12 of the cross-bar 14, which is secured to the folding standard 15, forming the other supporting member. This supporting member 15 carries on its upper end a cross-bar 16, having rounded ends 17 for engagement with

the notched bars 10, carried by the main ironing-board 5. At its lower end the standard 15 carries a cross-bar 18, forming a rest of considerable width for this bar at the lower 5 end, which rest is preferably beveled off, as shown at 19, Fig. 1, in order to rest securely and firmly upon the floor. The bar 18 is connected by braces 20 with the standard 15. The standard 15 carries on its upper face at 10 a point above where the standard 15 is pivoted to the other two standards a block 21, to which is secured one leaf of the hinge 22, the other leaf of this hinge being secured to the fastener 23, which comprises a plate or block 15 having a series of notches in its underneath face for engagement with the cross-rod 24, secured to the upper face of the standards 11'. The cross-brace 25 is preferably employed for connecting the two standards 11' 20 at a point close to the cross-rod 24, as this brace prevents the standard 15 when folded from striking the cross-rod 24 and bending the same in any manner, so that the fastener 23 would not easily and firmly engage the 25 same.

It will be observed that with this construction the ironing-table may be adjusted to different heights, as when the pins or studs 17 are in the inside notches of the bars 10 the 30 board will be elevated to a considerably greater extent than when the said pins or studs are in the outside notches, in which latter position they are shown in Fig. 1 of the drawings. When the ends of the supporting 35 members are drawn together at the bottom, so as to elevate the board, the fastener 23 slides over the rod 24 and drops into the succeeding notch, so as to hold the board at the position to which it has been elevated. To 40 fold the table, the fastener 23 is disengaged from the rod 24, the outer end of the board 5 elevated, so as to disengage pins or studs 17 from the bars 10, and when the fastener 23 is folded over flat upon the standard 15 the table is free to be folded in the manner shown 45 in Fig. 4 of the drawings.

While I have described in detail my invention, yet it will be observed that various changes may be made therein without deviating from the general spirit of the invention.

Having thus fully described my invention,

what I claim as new, and desire to secure by Letters Patent, is—

1. An ironing-table comprising a board and 55 two supplemental boards, a support therefor foldably attached thereto, said support comprising pivotally-secured standards, one standard having a cross-bar and bracing-rods therefor at its base, a locking-bar having a rounded 60 end carried thereby at its upper end, a rack-bar upon the lower face of said board adapted to be engaged by said locking-bar to permit of vertical adjustment of the board, and locking means to secure said support in an unfolded position, comprising a cross-bar carried by one of the standards, a block secured to the other standard, a hinged notched member, attached to said block at a point above the pivotal connection of the standards, said 70 member adapted to fold upon said standard, the notches of said member adapted to engage the said cross-bar carried by the other standard, thereby locking firmly the supporting members of said ironing-board, substantially 75 as described.

2. An ironing-table comprising a board and two supplemental boards, a support therefor, foldably attached thereto, said support comprising a pair of standards secured together 80 by brace-rods, a third standard pivotally secured thereto, means for adjusting the elevation of the board, comprising rack-bars upon the lower face of the board, a locking-bar having rounded ends carried upon the 85 upper end of third standard, said locking-bar adapted to engage with the racks upon the table, and locking means to secure said support in an unfolded position, comprising a cross-bar carried by said pair of standards, 90 a block secured to the third standard above the pivotal connection of the standards, a hinged notched member attached to said block, and foldable upon said standard, said notched member adapted to engage with the 95 cross-bar of said pair of standards to securely lock the support in position, substantially as described.

In testimony whereof I affix my signature in the presence of two witnesses.

JOHN GRAY.
